UNITED STATES PATENT OFFICE.

ROYAL E. DEANE, OF NEW YORK, N. Y.

IMPROVED CARVING-TABLE.

Specification forming part of Letters Patent No. 58,387, dated October 2, 1866.

To all whom it may concern:

Be it known that I, ROYAL E. DEANE, of the city, county, and State of New York, have invented a new and Improved Carving-Table; and I do hereby declare that the following is a full, clear, and exact description thereof, which will enable others skilled in the art to make and use the same, reference being had to the accompanying drawings, forming part of this specification, in which—

Figure 1 is a plan or top view of my invention; Fig. 2, a longitudinal vertical section of the same, taken in the line $x x$, Fig. 1; and Fig. 3, a transverse vertical section of the same, taken in the line $y y$, Fig. 1.

Similar letters of reference indicate like parts.

This invention relates to a new and useful improvement in carving tables, such as are used in restaurants, hotels, &c., for holding meats while being carved and keeping them in a warm state.

The invention consists in constructing the top of the table, on which the dishes of meat are placed, in the form of a shallow vessel of rectangular shape, and provided with a longitudinal central partition, as hereinafter fully shown and described, whereby a current of hot water is allowed to pass around within the top of the table underneath the dishes of meat and keep the same in a warm state, the chamber or vessel formed by the table-top communicating with the water-back or water-heater of a range or furnace.

The object of the invention is to obtain a table for the purpose specified, which will be simple in construction, possess no parts liable to get out of repair, and which may be kept in a proper warm state with a moderate supply of hot water.

A represents the top of the table, which is constructed in the form of a rectangular shallow pan or vessel supported at a suitable height by any proper framing, B. The top A of the table has bars a secured transversely upon it at a proper distance apart to support the dishes, and a partition-plate, b , is placed longitudinally and centrally within the top A, said plate not extending the whole length of the

top, a space, c , being allowed at one end to form a communication between the two compartments $d d'$, as shown clearly in Fig. 1.

Each compartment $d d'$, at the end opposite that where the space c is allowed, communicates, by means of pipes $e e'$, with the water-back or water-heater of a range or furnace, so that a current of hot water will pass continually through the compartments $d d'$, as indicated by the red arrows, the water from the heater passing up through pipe e into the compartment d , and passing through the compartment d' and through the pipe e' into the water back or heater.

By this arrangement the dishes containing the meat will be exposed to a large heating-surface. The current of water through the compartments $d d'$ is induced simply by the action, no static pressure or other force being required for the purpose.

The top of the table being entirely open, it will, of course, be seen that the sides of the top, and also the partition b , must be of such a height as will admit of a requisite depth of water in the top. Not a great depth of water is required, however, owing to the continuous current.

This carving-table may be constructed and applied at a very small cost, the heating apparatus being of the simplest form possible, involving only the cost of a few feet of pipe to connect the top of the table with the water back or heater.

What I claim as new, and desire to secure by Letters Patent, is—

A carving-table having a top, A, constructed in the form of a shallow vessel, divided by a longitudinal central partition-plate, b , one or more, with a space, c , allowed at one end to form a communication between the two compartments $d d'$, and the latter made to communicate, by means of pipes $e e'$, with the water back or heater of a range or furnace, substantially as herein shown and described.

ROYAL E. DEANE.
